TOY

Wladimir Euben, North Woburn, Mass.

Application April 27, 1939, Serial No. 270,454

4 Claims. (Cl. 46—63)

This invention relates to toys, and more particularly to those toys commonly referred to as "whirligigs," which furnish a source of amusement for children. The invention consists in 5 the novel construction and combination of the several parts, as will be hereinafter fully set forth.

One object of this invention is to provide a toy made up of two discs with a cross-bar and 10 one or more combs carrying musical reeds interposed therebetween and with two separate strings threaded through said discs and cross-bar, the ends of which a child may grasp and by pulling outwardly cause the discs to spin in one 15 direction and by moving inwardly allow said discs to spin in the opposite direction, music being created by air rushing through openings in the combs and vibration of the reeds caused by the revolving motion of said discs. The combs 20 are arranged flatwise transversely of the discs and the openings therein and the reeds face in the direction of rotation of the discs whereby making vibration of the reeds is obtained.

Another object of this invention is to create 25 a toy simple to manufacture and low in cost. Such toy may be made from wood, fiber, rubber, cardboard, Celluloid, Bakelite, metal or other material, or from any combination of two or more of such materials.

30 A still further object is to provide a toy of the type described and illustrated that can be operated easily by even a small child.

These and other objects will be apparent by 35 referring to the accompanying drawing, in which similar characters of reference indicate corresponding parts in all the figures.

Figure 1 is a perspective view illustrating my invention;

Figure 2 is a sectional view showing the cross- 40 bar, combs and reeds radially in section and elevation, and taken on the line 2—2 of Figure 3;

Figure 3 is a sectional view taken on the line 3—3 of Figure 2;

45 Figure 4 is a sectional view taken on the line 4—4 of Figure 2;

Figure 5 is a detailed sectional view showing the manner in which the strings are attached to the toy;

50 Figure 6 is a sectional view of a modified form showing a single reed and a blank cross-bar; and

Figure 7 is a sectional view of a modified form showing a pair of reeds arranged adjacent to one another.

55 Referring now in detail to the drawing, I pro-

vide, in the preferred form as shown in Figures 1 to 5 inclusive, two discs 1, with combs 2 interposed between said discs and secured in a solid cross-bar 3 by means of elements 4 which are glued or welded to the cross-bar and combs. 5 Mounted on said combs 2 are metal strips 5 having elongated slots 6 and reeds 7 riveted to said strip 5 at 8, said discs, when revolved, producing a musical sound to the amusement of the child.

10 In Figure 5, it will be seen that the discs 1 and the cross-bar 3 have two holes therethrough shown at 9 and 10. Threaded through said holes and looped at 12^a on one side is a string 12 twisted at its opposite ends as shown. A similar 15 string 13, twisted and looped at 13^a in a like manner as before-described, is also shown.

In a modified form, as shown in Figure 6, I provide discs 1' with a single comb 2' and a plate 5' having an elongated slot 6' and reed 7' 20 riveted at 8' interposed between said discs. Arranged at 90° to the comb 2' is a solid bar 3'. In said bar 3' are the holes 9' and 10' for the strings to pass therethrough.

25 In the modified form, as shown in Figure 7, I show the plates 5'' with reeds 7'' thereon placed adjacent one another for the purpose of producing a musical chord. The discs 1'', the combs 2'', the cross-bar 3'', the elements 4'', and rivets 30 8'' are also shown.

35 It will be observed that in each of these forms of my invention the comb members, including the comb carrying metal plates or strips, are arranged flatwise transversely of and between the discs, and that the slots or openings therein and the cooperating sound producing reeds face in the direction of rotation of the rotary body. By 40 this construction and arrangement of the parts air currents are produced in the rotation of the body which pass with force through the openings in the comb members and effect a very forcible and wide amplitude of vibratory motion of the reeds to cause the production of a maximum 45 volume of sound, whereby maximum efficiency of the reeds is obtained so that a small number of reeds or reeds of small size will create a large volume of sound.

While there has been shown and described 50 and pointed out the fundamental novel features of the invention, it will be understood that various omissions and substitutions and changes in the form and details of the device illustrated, and in its operation, may be made by those skilled in the art without departing from the 55 spirit of the invention. It is the intention,

therefore, to be limited only as indicated by the scope of the claims.

Having thus described my invention I claim:

5. 1. In a device of the character described, a rotatable body comprising a pair of spaced discs, a cross bar arranged between and connecting said discs, a comb member fixed to and extending at right angles to the cross bar and arranged radially of and flatwise transversely of 10 and between the discs, said comb member having an opening therein, and a sound producing reed carried by the cross bar and disposed in alignment with the opening in the comb member, said opening and reed facing in the direction of rotation of the rotatable body.
15. 2. In a device of the character described, a rotatable body comprising a pair of spaced discs, a cross bar arranged between and connecting said discs, a plurality of comb members fixed to and 20 extending at right angles from the bar and arranged flatwise transversely of and between the discs, each of said comb members having an opening therein, and sound producing reeds carried by the cross bar and arranged in alignment 25 with the openings, said openings and reeds facing in the direction of rotation of the body.
3. In a device of the character described, a ro-

tatable body comprising a pair of spaced discs, a cross bar arranged between and connecting said discs, a plurality of comb members fixed to and extending at right angles from the bar and arranged flatwise transversely of and between the 5 discs, plates disposed in parallel relation to the comb members and having openings therein, and sound producing reeds fixed to the plates and disposed between the plates and comb members in alinement with the openings in the plates, said 10 openings and reeds facing in the direction of rotation of the body.

4. In a device of the character described, a rotatable body comprising a pair of spaced discs, a cross bar arranged between and connecting said 15 discs, a plurality of comb members fixed to and extending at right angles from the bar at different points about the axis and arranged flatwise 20 transversely of and between the disks, a plurality of plates disposed side by side in parallel relation to each comb member and having openings therein, and sound producing reeds fixed to the plates and disposed between the plates and comb members in alinement with the openings in the 25 plates, said openings and reeds facing in the direction of rotation of the body.

WLADIMIR BUBEN.
